Int. Cl. D2—01

U.S. Cl. D2—179

The single figure is a front perspective view of a rain cape showing my new design, the back being conventional and plain.

The characteristic feature of my design resides in a combination on the rain cape disclosed of a plain fly front, flanked on one side by a wide and narrow diagonal stripe, substantially as shown.

I claim:

The ornamental design for a rain cape, as shown and described.
